G. B. HALL

HOUSEHOLD COMMODITY INDICATOR

Filed May 23, 1927

UNITED STATES PATENT OFFICE.

GEORGE B. HALL, OF WINNIPEG, MANITOBA, CANADA.

HOUSEHOLD COMMODITY INDICATOR.

Application filed May 23, 1927. Serial No. 193,600.

The invention relates to improvements in household commodity indicators and an object of the invention is to provide a simple, cheap and durable device which can be placed by the householder in a conspicuous location and which can be readily set by the user so that a tradesman can ascertain at a glance the exact quantity of a commodity or commodities to be delivered to the consumer and which will also hold the customary tickets or money given in exchange for the commodity and which will further advise the tradesman as to the name of the householder.

A further object is to construct the device so that it can be suspended from the wall or door of the building or from a milk bottle as desired and which can be utilized to indicate the need and the amount of the regular or special commodity required.

20 A further object of the invention is to construct the device in the form of a box having a hinged lid, the lid containing an indicating card so that the card is fully exposed when the box is open and effectively protected from the weather when the same is closed.

25 A further object is to mount the indicating card in the box lid so that it can be readily removed by the householder, such permitting of the ready insertion in the box of varying cards to accommodate the produce of varying tradesmen.

With the above more important objects in view, the invention consists essentially in the arrangement and construction of parts hereinafter more particularly described reference being had to the accompanying drawing, in which:—

Fig. 1 is a perspective view of the indicator as it appears in its open position, parts being broken away to expose construction.

40 Fig. 2 is a side view of the indicator as it appears suspended from a wall and with the lid of the box open.

Fig. 3 is a front view of the device mounted on the upper end of a milk bottle and with the lid closed.

Fig. 4 is a vertical sectional view at 4—4'

Figure 1.

Fig. 5 is a perspective view of the indicating card.

Fig. 6 is a perspective view of the bracket.

Fig. 7 is an enlarged detailed vertical sectional view at 7—7' Figure 5.

In the drawing like characters of reference

55 indicate corresponding parts in the several figures.

The indicator embodies a substantially rectangular metal box 1 which is fitted with a hinged lid 2, the lid having marginal flanges 3 which overhang the top edge of the box 60 when the lid is closed. The box is made preferably with tapering ends 4 and 5, the ends being narrower at the front than the rear so that the lid takes an inclined position when closed. This gives the box a neater and more 65 pleasing appearance and insures of the more effective closing of the lid when the same is swung down.

To the under side of the box I secure a pair 70 of cross strips 6 and 7, the strip 6 passing centrally lengthwise of the box and having the ends turned down and curved to provide gripping fingers 8 and 9 and the strip 7 passing centrally across the box and having the forward end down turned to provide a curved 75 gripping finger 10, and the rear end extending beyond the back of the box and then turned down to provide a straight finger 11. The strips are fastened to the box by tongues 12 which are passed through suitable slots 13 80 formed in the box bottom and then flattened down to grip the bottom. The spring gripping fingers 8, 9 and 10 are positioned so that they will receive and grip the upper end 14 of a milk bottle when applied thereon and in 85 so doing effectively support the indicator on the bottle.

The rear side of the box is fitted with a pair 90 of spring clips 15 and 16 which are readily provided by slitting the box and then pressing the portions inwardly to provide the clips. The clips are utilized to receive and hold a name plate 17 which in practice will be the name of the party owning the box, that is the consumer of the products. 95

In the lid of the box I mount an indicating card 18 which can be formed from cardboard, celluloid or other stiff material. The card is of such dimension that it fits snugly within the cover when pressed into the same, and provision is made for releasably holding the card in position such being accomplished by indenting the front flange of the lid or cover to provide retaining tits 19 and 20 which in the inserted position of the card are 100 directly in advance of the upper edge thereof. When the card is being placed in the cover it is sprung past these tits which thereafter 105

serve to retain the card. The front flange of the lid is centrally cut to provide a finger piece 21 which is turned out into the plane of the body of the cover and makes it convenient for the tradesman to open the box, as he can readily catch the finger piece and raise the lid. By cutting the flange at this point I make it also convenient for the householder to change the indicating card when desired as one can readily catch the upper exposed edge of the card by the finger nail and pull the card ahead forcibly past the tits.

The indicator card is provided at the top with four similar spaces in which printed information appears. It has also a vertical central column divided by horizontal lines in the spaces of which further printed information appears. In the card herein shown the words Milk and Cream appear at the top of the card and underneath the word Milk is printed "For special milk use red pointer" and under the word Cream is printed "For buttermilk use blue pointer". In the spaces of the vertical column I have indicated the various quantities of milk, cream or buttermilk which might be required by the consumer and at the bottom of the central column appears the word "Tickets".

Centrally at the ends of the card I locate pivot pins 22 and 23 which are herein shown as in the form of the well known two legged paper clip. On each of these pins I mount two pointers indicated by the reference numerals 24, 25, 26 and 27. The pointers 24 and 27 can be the same colour but those 25 and 26 are of different colours. That 25 will be say red and that 26 blue. The pointers 24 and 27 can be white. The pointers are provided to indicate the quantities of produce required by turning them so that they will point to selected spaces in the vertical column, and to insure that there will be no mistaking what is required I have drawn leader lines from the ends of the spaces of the vertical column, these extending in a direction more or less radial to the pivot pins.

To insure that the pointers will remain where put I have indented the material of the card to provide spaced pockets 28 positioned concentric to the pins and have formed protuberances 29 on the pointers adapted to enter one or the other of the pockets when the pointers are shifted. The pockets are also positioned with due regard to the spaces of the vertical column so that when any pointer is set with its protuberance in the pocket the pointer will point to a definite space in the column.

The card herein shown is particularly designed for indicating to a tradesman, such as a milkman, just what of his commodities the householder desires. The pointer 24 in Figures 1 and 5 is set to indicate that one quart of milk is wanted and the pointer 27 to indi-

cate that a half pint of cream is desired. The pointer 25 indicates that a pint of special milk is wanted and 26 that two quarts of buttermilk are to be left. Obviously the householder can readily set the pointer or pointers to indicate just what is required. If tickets are required one of the pointers will be swung down to point to the word "Ticket" at the lower end of the vertical column. When one or other of the pointers are not in use it or they will be swung to a vertical position.

As before stated the indicating card can be readily removed from the box when desired and obviously a similar card having different markings thereon could be inserted and the pointers thereof turned to indicate the produce desired. In other words the indicating card herein shown is specially designed for the milkman, and another card could be provided for the breadman and so on for other tradesmen.

The householder can obviously set the pointers at any time before the customary hour at which the various tradesmen call and then close the lid. She can also leave tickets or money in the box where they are protected from the weather. When the tradesman calls he has simply to open the box, leave the produce indicated and take the money or tickets left therein.

I might point out that in some houses there may be several families and it would be desirable for each of these to have an indicator of their own. Under such circumstances it is very desirable that the name of the customer be displayed in the box as the tradesman can then be sure that each customer gets what they order and if an account be kept he is able to make proper entry.

If it is not desired to attach the indicator to the milk bottle it can be readily suspended from a wall or door by providing a plate 30 attached permanently to the wall or the door, the plate having an off set strap 31 adapted to receive the rear straight arm 11 of the holder and support the holder in the position best shown in Figure 2.

What I claim as my invention is:

1. A household commodity indicator for insertion within the lid of a box embodying a commodity indicating card mounted within the lid and having selected commodity names appearing at the top thereof, a centrally located vertical column having indicia representing the quantity of selected commodities required and indicating pointers pivoted centrally to the ends of the card and adapted when manipulated and set with regard to the column to indicate the amount of selected commodity required.

2. A household commodity indicator for insertion within the lid of a box embodying a commodity indicating card mounted within the lid and having the names of selected commodities printed on the top there-

of, and information relative to specially required commodities appearing thereon underneath the former names, a central vertical column having indicia indicating the quantity of selected commodities required and a pair of concentrically mounted pointers pivotally attached to each end of the card, the pointers of a pair being differently col-

oured, said pointers being adapted to indicate when set with regard to the central column the quantity of the selected commodity required. ¹⁰

Signed at Winnipeg, this 4th day of May, 1927.

GEORGE B. HALL.
